UNITED STATES PATENT OFFICE.

CHARLES E. BOWN, OF DAYTON, OHIO.

DESIGN FOR A GREASE-GUN.

57,107.

Specification for Design. Patented Feb. 22, 1921.

Application filed July 24, 1920. Serial No. 398,815. Term of patent 14 years.

To all whom it may concern:

Be it known that I, CHARLES E. BOWN, a citizen of the United States, residing at Dayton, in the county of Montgomery and State of Ohio, have invented a new, original, and ornamental Design for a Grease-Gun, of which the following is a specification, reference being had to the accompanying drawing, forming part thereof.

The figure is a side elevation of a grease gun, showing my new design.

I claim:

The ornamental design for a grease gun, as shown.

CHARLES E. BOWN.
